United States Patent

Des. 236,905
Patented Sept. 23, 1975

236,905

BUOYANT AMUSEMENT DEVICE

John F. Hunt, 19207 60th W., Lynnwood, Wash. 98036

Filed Aug. 31, 1973, Ser. No. 393,617

Term of patent 14 years

Int. Cl. D21—02

U.S. Cl. D34—15.41

Fig. 2.

Fig. 3.

FIG. 1 is a perspective view of a buoyant amusement device showing my new design;

FIG. 2 is a front elevational view thereof; and

FIG. 3 is a right side elevational view thereof, the side opposite being substantially identical.

I claim:

The ornamental design for a buoyant amusement device, as shown and described.
